(57) **CLAIM**

The ornamental design for a bus stop sign, as shown and described.

DESCRIPTION

FIG. 1 is a front view of a bus stop sign showing my new design.

FIG. 2 is a back edge view of the bus stop sign.

FIG. 3 is a front edge view of the bus stop sign.

FIG. 4 is a top edge view of the bus stop sign.

FIG. 5 is a bottom edge view of the bus stop sign; and, FIG. 6 is a reduced scale perspective view of the bus stop sign.

The broken lines in the drawings depict environmental structure, which forms no part of the claimed design.
